UNITED STATES PATENT OFFICE

MARTIN HOKANSON, OF DULUTH, MINNESOTA, ASSIGNOR TO MARSHALL-WELLS COMPANY, OF DULUTH, MINNESOTA, A CORPORATION OF NEW JERSEY

SHOVEL

Application filed July 18, 1924. Serial No. 726,776.

This invention relates to shovels, spades, or scoops of the hollow-back type.

In the manufacture of tools of this class, difficulty has been experienced in preventing the socket walls from opening up or spreading when a downward pressure is exerted on the handle of the shovel.

The object of my present invention is to provide means cooperating with the reinforcing blade and socket rivet to resist the downward thrust tending to separate or open the walls of the socket and transmit such thrust to the ends of the rivet, the result being that the pressure on the handle will tend to draw the walls of the socket together rather than separate them.

In the accompanying drawings forming part of this specification,

Figure 1 is a view partially in section of a hollow-back shovel embodying my invention;

Figure 2 is a detail view showing a means employed for uniting the walls of the socket;

Figure 3 is a similar view showing a modified means for locking the edges of the socket walls together;

Figure 4 is a sectional view on the line 4—4 of Figure 1;

Figure 5 is a sectional view showing a modified construction;

Figure 6 is a detail perspective view showing the reinforcing or strengthening means illustrated in Figure 5;

Figure 7 is a perspective view showing a modified construction of the reinforcing band or ring;

Figure 8 is a sectional view showing the preferred manner of applying this solid ring to the handle sections;

Figure 9 is a sectional view showing a modified construction of the wall of the socket into which the handle sections are inserted;

Figure 10 is a detail sectional view showing a modified form of the reinforcing band opened to allow the insertion of the reinforcing blade therein;

Figure 11 is a similar view showing the band closed and clamped together by the transverse rivet;

Figure 12 is a detail view partially in section showing the handle fitting within the

shovel socket and the rivets for securing the band and handle sections together.

In the drawing, 2, represents the blade of the shovel having a longitudinal extension at one end that is folded downwardly by suitable means to form a handle-receiving socket having walls 3 and 4. The handle, composed preferably of separable wood sections 5, is fitted into the socket and has a reinforcing blade 6 between the sections and when the parts are assembled the socket walls, wood sections and reinforcing blade are firmly secured together by means of suitable rivets 7 countersunk in the walls of the socket and similar rivets 8 which pass through the sections of the handle outside the socket and have their ends countersunk in the wood portions thereof. On the end of the handle a suitable grip 9 is provided.

In shovels, spades, or scoops of this type, the folded longitudinal edges of the socket walls are not secured together but are separated by a narrow gap or space and when downward pressure is applied to the handle in the use of the tool, these walls will be separated, the pressure on the reinforcing blade tending to force them apart and open up the socket and destroy the usefulness of the tool. To obviate this difficulty in the use of a shovel of this type, I propose to unite the longitudinal edges of the socket by suitable means such as welding, as indicated at 10 in Figures 2 and 4, the welding operation forming the final step in the manufacture of the shovel and causing the edges of the socket to be securely bound together and united as in one piece.

In Figure 3, I have shown a modification which consists in providing tongues 11 dove tail in form, fitting into correspondingly shaped socket 12 in the edges of the socket walls 3 and 4, the tongues being inserted into the sockets during the folding operation and becoming locked therein against any movement which would tend to separate or spread the socket walls.

In Figures 5 and 6, I have shown another modification which consists in forming a band 13 of suitable material, preferably a thin gage of metal, folded to fit snugly against the surface of the wood handle section within the

socket, the ends of the band preferably being separated as indicated at 14 to allow its convenient placing on the handle section and permit it to accommodate itself to slight variations in the size of the handle section. 5 Holes 15 are provided in the band to receive the ends of the rivet 7. Evidently downward pressure on the reinforcing blade 6 will be absorbed by the band and transmitted to the ends of the rivet and the tendency of the socket walls to open up or separate under such pressure will be eliminated.

10 The band 13, may be closed if preferred, and when made in this way, is preferably tapered to fit the taper of the handle and can then be driven on to make a snug fit.

15 In Figure 7, I have shown a modification of the reinforcing means which consists in providing a continuous ring 13^a which may be made by cutting off a section of tubing of suitable size and formed to fit the end of the handle and bind the sections and the reinforcing blade together. Rivet holes 15^a are provided in the ring to receive the ends of the rivet inserted through the socket walls and the reinforcing blade. This ring will bridge the opening between the edges of the socket walls and will effectually prevent the separation of the walls resulting from downward pressure on the handle and the reinforcing blade. In this way, I provide a very simple inexpensive means for reinforcing a hollow-back shovel at a point which has proved structurally weak in the use of the tool.

20 In Figure 9, I have shown a modification in the socket. Instead of having the edges thereof terminate on the under side of the hollow-back, I provide extensions 16 thereon which are folded inwardly in parallel relation and adapted to receive the reinforcing blade between them and having holes for the rivets 7 which bind the walls of the socket and the reinforcing blade together. These inwardly turned edges having bearings on the middle portion of the rivets will prevent the socket walls from separating and the handle becoming loose in the shovel blade. A shovel, 25 spade, or scoop made in this way will be extremely strong and durable and capable of withstanding any pressure to which an article of this kind may be subjected. It will be understood of course that instead of folding the walls of the socket downwardly they may be turned upwardly so that the gap between the walls will be on the upper side of the hollow-back instead of on the lower side. This, however, will make no difference in the use of my invention as similar means or methods of reinforcing or binding the walls of the 30 socket together may be employed whether the socket is folded downwardly or upwardly in the construction of the shovel.

35 In Figure 10, I have shown a modified form of the band indicated by 13^b open on one side and having inwardly turned edges extending

preferably to the opposite side of the band. These inwardly turned edges or flanges I will indicate by reference numeral 13^c. The handle sections are inserted into the openings in the band in assembling and the reinforcing 70 blade 6 is dropped into the recess formed by the separation or drawing apart of the sections of the band. When this has been done, the sections are closed or drawn together as indicated in Figure 11 and secured by suitable means such as a rivet 13^d.

75 I prefer to use rivets for securing the parts of the shovel together. The rivets 8 and 13^d are inserted when the sections and band are assembled and before placing them in the socket of the shovel. The rivet 8 preferably passes through the handle sections and the reinforcing blade alone while the rivet 13^d passes through the handle sections, the blade and the reinforcing band. After the assembled parts are inserted into the socket they are all secured together by the insertion of the rivet 7 fitting openings in the walls of the socket and passing through the handle, the reinforcing blade and the band.

80 I claim as my invention:

85 1. A tool blade having an extension formed by folding longitudinally to bring the longitudinal free edges in adjacent substantially parallel relation to form a socket, a handle 90 having a reinforcing blade, means encircling the handle and blade and lying within the socket, and a rivet passing through the walls of the socket encircling means, handle and reinforcing blade.

95 2. A tool blade having an extension formed by folding longitudinally to bring the longitudinal free edges in adjacent substantially parallel relation to form a socket, a handle 100 having a reinforcing blade having an edge opposed to the free edges of the socket, and a collar encircling the handle and blade and lying within the socket, and a rivet passing through the walls of the socket, collar, handle and reinforcing blade.

105 3. A tool blade having an extension formed by folding longitudinally to bring the longitudinal free edges in adjacent substantially parallel relation to form a socket, a handle 110 comprising two semi-circular sections and a middle reinforcing blade, said blade having an edge opposed to the free edges of the socket and means encircling the handle and blade and lying within the socket and bridging the 115 socket edges, and a rivet passing through the walls of the socket encircling means, handle and reinforcing blade.

120 In witness whereof, I have hereunto set my hand this 23rd day of June, 1924.

MARTIN HOKANSON.
